FIG. 1

FIG. 2

Des. 198,181

PAGE 2

FIG. 3

FIG. 4

FIG. 5

FIG. 6

FIG. 1 is a side elevational view of a lantern embodying my design;
FIG. 2 is a top plan view of the lantern;
FIG. 3 is a front elevational view of the lantern;
FIG. 4 is a back elevational view of the lantern;
FIG. 5 is a bottom plan view of the lantern; and
FIG. 6 is a side elevational view of the lantern showing the side opposite the one shown in FIG. 1.

I claim:
The ornamental design for a lantern, as shown.
